LUBRICATING SYSTEM.

Application filed March 14, 1922. Serial No. 543,643.

This invention pertains to improvements in lubricating systems. It is among the objects of the invention to provide a convenient system for connecting and disconnecting a source of lubricant under pressure with lubricating cups or nipples carried by or connected to the parts to be lubricated.

In the drawings, which show a preferred form of one embodiment of the invention:

10 Figure 1 is a side elevation of a preferred form of lubricating apparatus;

Fig. 2 is a section through the lubricant-discharging and lubricant-receiving portions of the preferred form of apparatus illustrated in Fig. 1;

Fig. 3 is a side elevation of the lubricant-receiving parts illustrated in Fig. 1, the lubricant supply apparatus removed therefrom;

20 Fig. 4 is a section on the line 4—4 of Fig. 2.

Figs. 5, 6 and 7 illustrate respectively the spring, ball and a longitudinal section through the body portion of the preferred 25 form of lubricant-receiving cup or nipple;

Fig. 8 is an end elevation of the lubricant-receiving nipple;

Fig. 9 is a section, partly in elevation, through that portion of the nozzle illustrated in Fig. 10;

Figs. 10 through 19 illustrate parts of the preferred form of nozzle shown in section in Fig. 2; and

Figs. 20, 21 and 22 are diagrammatic sections on the line 20—20 of Fig. 2, illustrating the relation of the parts of the preferred form of nozzle illustrated relative to each other and relative to the lubricant-receiving cup or nipple during coupling or uncoupling 40 operations.

Referring to the drawings and to the preferred form of the invention selected for illustrative purposes, we have shown a lubricant-receiving cup or nipple 25 shown in side elevation in Fig. 3, the body of which is shown in section in Fig. 7 and in end elevation in Fig. 8. The preferred form of cup or nipple is provided with a lubricant-receiving opening 26 at one end thereof and 45 preferably includes a cylindrical portion 27 adjacent the lubricant-receiving opening and is provided with projections adjacent the end of the cup or nipple having the lubri-

cant-receiving opening, these projections in the preferred form of the invention illustrated being formed by making the cross-section of the body of the cup or nipple polygonal, being square as illustrated to provide lugs or projections 28 having extended lateral faces and providing underlying faces of considerable area. The side faces and the polygonal faces are preferably tangential to the main cylindrical portion of the cup or nipple body, the other end of said body being threaded at 29 for engagement with the part to be lubricated, herein shown as a bolt 30. In the construction illustrated, the angled connection 31 is provided between the cup or nipple and the bolt 30, but it is obvious that this angled connection is only useful in certain places.

Cooperating with the preferred form of cup or nipple hereinbefore described, we have provided a lubricant gun including a barrel 32 containing the usual lubricant-expelling plunger 34 and having a screw-threaded shank 35. It will be understood, however, that so far as many aspects of the invention are concerned, any type of lubricant expelling mechanism may be used. Cooperating with the lubricant gun or other suitable supply of lubricant under pressure, we provide a nozzle which may include several parts but which preferably provides an opening at the end thereof herein shown as square (see Fig. 11), there being provided within the nozzle a chamber adapted to permit turning of the nozzle when it is entered over the cup or nipple, so that the projections 28 on the cup or nipple will overlie portions of the nozzle, such portions herein being shown as the flats 36. Within the outer portion of the nozzle, we preferably provide means for engagement with the projections on the cup or nipple. In the preferred form of the invention illustrated, these engaging portions take the form of projections 37 fitting between the outer portion of the nozzle and the projections on the lubricant cup, having extended bearings along two sides of the polygonal portion of the cup. It is obvious that the number or shape of these engaging portions may be varied somewhat, particularly if the shape of the projections on the cup or nipple is varied. The 100 projections 37 serve to prevent rotation of

the discharge nozzle 38 relative to the cup or nipple, and also, in the embodiment of the invention illustrated, serve to prevent turning of a sealing washer carried in the discharge nozzle 38 and adapted to press against that face of the lubricant cup or nipple which surrounds the lubricant-receiving aperture in the end thereof. These projections 37, because they do not rotate relative to the cup or nipple when the nozzle or other portions of the apparatus are rotated, may conveniently be used as means for effecting opening and closure of valve means carried by the nozzle. In the preferred form of the invention illustrated, we have effected all these purposes very simply by making the projection-engaging parts 37 integral with the discharge nozzle 38 which carries the sealing washer 39, and which serves as a part of the valve mechanism. The amount which the exterior portions of the nozzle may rotate relative to the cup or nipple may be conveniently limited by the provision of suitable stop means between the discharge nozzle 38 and the exterior portions of the nozzle, such stop means, in the preferred form of the invention illustrated, comprising the screw 40 projecting from the discharge nozzle 38 and into a slot 41 (Fig. 10) in the exterior portion of the nozzle. The preferred form of valve illustrated is of the rotary type, the ports 42, 43 being provided in the discharge nozzle 38 and ports 44, 45 being provided in the valve disc 46 having a projection 47 entering a recess in the exterior portion of the nozzle so that, as the nozzle is turned, the valve disc 46 will be turned. In the preferred form of the invention illustrated, the ports 44, 45 bear the relation to the ports 42 and 43 as illustrated diagrammatically in Fig. 20 when the nozzle and cup or nipple are not locked together. As the nozzle is turned clockwise relative to the nipple, the projections on the nipple overlie portions of the nozzle (as illustrated by the dotted squares in Fig. 21) before the ports 43 and 44 or the ports 42 and 45 begin to communicate. Completion of the coupling movement, so that the ports are in full register and the projecting portions of the cup or nipple are to a considerable extent underlain by the end of the nozzle, brings the parts to the relative position illustrated in Fig. 22. At this time the projection 40 will have engaged the end of the slot 41 so that the nozzle cannot turn any more in clockwise direction relative to the cup or nipple. In the preferred form of the invention illustrated, the valve disc 46 may be pressed toward its seat on the part 38 by a spring 60. When pressure is left on the lubricant in the barrel of the gun, the lubricant pressure also will contribute to a tight seat between the valve portions 46 and 38.

We prefer to provide for pressing the sealing washer 39 against the top of the lubricant-receiving cup or nipple by lubricant pressure, and to this end we have provided a recess behind the washer 39 into which the lubricant may be forced so that the pressure of the lubricant acting on the surface of the washer which is away from the nipple may press the other surface of the washer against the top of the nipple. 75

While the invention may for some purposes be used in connection with a nozzle flexibly connected to the source of lubricant under pressure, either by flexible hose or suitable joints, etc., we prefer to have the nozzle so connected to the gun barrel that the coupling between the lubricant gun and the cup or nipple may be effected by rotary movement of the barrel, without the necessity for taking hold of the nozzle. This 85 provides the additional advantage that it is only necessary to use one hand to operate the gun, the strain, tending to turn the barrel of the gun in clockwise direction as the lubricant is expelled, being taken by the cup or nipple. The polygonal cross-section of the cup or nipple where the projections thereon are provided, not only greatly increases the strength of the projections beyond that which is provided by the usual pins, but also facilitates passage of the nozzle of the gun over the cup or nipple, and in this respect is much superior to the usual arrangement of pins such as are used in bayonet joint connections in lubricating 95 systems. 100

Assuming the gun and the cup or nipple to be detached from each other, the valve will always be closed. When the nozzle of the gun is passed over the lubricant-receiving end of the cup or nipple, the pressure of the lubricant in the barrel will not be pressing on the washer 39 and this washer will not, therefore, to any considerable extent interfere with the free entrance of the 105 cup or nipple into the nozzle. During this entering movement, the projection-engaging parts 37 will have passed over two opposite sides of the squared portion of the nipple, and therefore there can be no relative turning movement between these projections 37, or parts connected thereto, and the cup or nipple. The exterior portions of the nozzle may, however, be turned, and as they are turned the projecting portions of the nipple 110 will overlie the lips 36 of the nozzle. The valve disc 46 will also have turned during the coupling movement until the ports are in register as illustrated in Fig. 22, at which time further turning of the nozzle relative to the cup or nipple in clockwise direction 115 will be prevented because the projection or screw 40 will have reached the end of the slot 41. The cup or nipple will now support the gun while the handle 70 is turned to 120 125 130

force lubricant into the cup or nipple and part to be lubricated. When it is desired to release the connection, the nozzle may conveniently be turned into nipple-releasing position, incidentally closing the valve before disconnection is complete, by turning the gun barrel 32 in counterclockwise direction.

While we have shown and described a preferred form of one embodiment of the invention, it will be understood that changes involving omission, substitution, alteration and reversal of parts, and even changes in the mode of operation, may be made without departing from the scope of the invention, which is best defined in the following claims.

We claim:

1. A lubricating system comprising a cup or nipple having a lubricant-receiving opening in one end thereof, polygonal lateral projections adjacent said end having said opening, in combination with a lubricant gun having a barrel, a lubricant expelling plunger and a nozzle at one end of the barrel, said nozzle presenting at the end thereof an opening permitting passage of the nozzle over said end of said cup or nipple and over said projections, and presenting portions that underlie said projections when the nozzle is turned relative to the cup or nipple, said nozzle rotatable by partial rotation of the lubricant gun barrel in one direction for quick engagement of said nozzle to said cup or nipple and by partial rotation in the other direction for quick disengagement of said nozzle from said cup or nipple, rotary valve means operatively interposed between the interior of said barrel and said nozzle and valve opening and closing means actuated by rotation of said barrel.

2. A lubricating system comprising a cup or nipple having a lubricant-receiving opening in one end thereof, tangential lugs or projections adjacent said end of said cup or nipple, in combination with a lubricant delivering nozzle presenting portions adapted to underlie said projections when said projections are entered in said nozzle and said nozzle is turned relative thereto, said nozzle presenting a sealing washer for engagement with the end of said cup or nipple having a lubricant-receiving opening, and a rotary valve having a part carrying said sealing washer.

3. A lubricating system comprising a cup or nipple having a lubricant-receiving opening in one end thereof, tangential lugs or projections adjacent said end of said cup or nipple, in combination with a lubricant delivering nozzle presenting portions adapted to underlie said projections when said projections are entered in said nozzle and said nozzle is turned relative thereto, said nozzle presenting a sealing washer for engagement with the end of said cup or nipple having a

lubricant-receiving opening, and a valved part carrying said sealing washer, and means for holding said valved part against rotation relative to said cup or nipple.

4. A lubricating system comprising a cup or nipple having a lubricant-receiving opening in one end thereof, lugs or projections adjacent said end of said cup or nipple, in combination with a lubricant-delivering nozzle presenting portions adapted to underlie said projections when said projections are entered in said nozzle and said nozzle is turned relative thereto, said nozzle presenting a sealing washer for engagement with the end of said cup or nipple having a lubricant-receiving opening, and a valved part carrying said sealing washer, said sealing washer carried by a part rotatable relative to said nozzle, said sealing washer urged toward said end of said cup or nipple by the pressure of the lubricant, and means for holding said valved part against rotation relative to said cup or nipple when said valve is open.

5. A lubricating system comprising a lubricant-receiving part having lateral projections providing both lateral and underlying faces, in combination with a lubricant-delivering nozzle readily attachable to and detachable from said receiving part, said nozzle presenting an interior chamber to receive a portion of said receiving part and to permit turning of said nozzle relative to said receiving part until a portion of said nozzle underlies said lateral projections, and a part rotatably mounted in said nozzle and presenting faces engaging the lateral faces of said lubricant-receiving part for limiting rotation of said nozzle relative to said lubricant-receiving part.

6. A lubricating system comprising a lubricant-receiving part having an opening in one end thereof and a polygonal portion adjacent said end of said part, said polygonal portion presenting lateral and underlying surfaces, in combination with a lubricant-delivering nozzle having an opening in the end thereof to admit said end of said part including the polygonal portion thereof, said opening shaped and said end of said nozzle chambered to permit turning of said nozzle relative to said polygonal portion while said polygonal portion overlies portions of the end of said nozzle to lock said nozzle to said lubricant-receiving part, and a part carried by said nozzle adapted to bear against a lateral surface of said polygonal portion and to limit turning of said nozzle relative to said lubricant-receiving part.

7. A lubricating system comprising, in combination, a lubricant-receiving part having an opening in the end thereof, projections from said part adjacent said end, in combination with a lubricant-delivering nozzle having an opening in the end thereof

shaped to admit said end of said part and said projections, said nozzle chambered to permit turning of said nozzle relative to said projections when the latter are entered in said nozzle, so that said projections overlie locking portions of said nozzle, a sealing part carried by said nozzle and a projection-engaging part carried by said nozzle and connected to said sealing part, said projection-engaging part permitting turning of said nozzle to lock said nozzle to said lubricant-receiving part while said sealing part remains stationary, rotatively considered, relative to said end of said lubricant-receiving part.

8. A lubricating system comprising, in combination, a lubricant-receiving part having an opening in the end thereof, projections from said part adjacent said end, in combination with a lubricant-delivering nozzle having an opening in the end thereof shaped to admit said end of said part and said projections, said nozzle shaped to permit turning of said nozzle relative to said projections when the latter are entered in said nozzle, so that said projections overlie locking portions of said nozzle, a projection-engaging part carried by said nozzle and engaging said projections when said nozzle is turned relative to said lubricant-receiving part, said projection-engaging part remaining stationary relative to the lubricant-receiving part during a portion at least of the rotative movement of the nozzle relative to said lubricant-receiving part, and a nozzle-valve the opening and closing of which is actuated by the turning of a part connected to said nozzle relative to said projection-engaging part.

40. A lubricating system comprising, in combination, a lubricant-receiving part having an opening in the end thereof and projections from said part adjacent said end, in combination with a lubricant-delivering nozzle having an opening in the end thereof shaped to admit said end of said part and said projections, said nozzle shaped to permit turning of said nozzle relative to said projections when the latter are entered in said nozzle, so that said projections overlie locking portions of said nozzle, a projection-engaging part carried by said nozzle and engaging said projections when said nozzle is turned relative to said lubricant-receiving part, said projection-engaging part remaining stationary relative to the lubricant-receiving part during a portion at least of the rotative movement of the nozzle relative to said lubricant-receiving part, and a rotary valve in said nozzle the opening and closing of which is actuated by the turning of a part connected to said nozzle relative to said projection-engaging part.

65. A lubricating system comprising, in combination, a lubricant-receiving part hav-

ing an opening in the end thereof, projections adjacent said end, in combination with a lubricant-delivering nozzle having an opening in the end thereof shaped to admit said end of said part and said projections, 70 said nozzle shaped to permit turning thereof relative to said projections when the latter are entered in said nozzle, so that said projections overlie locking portions of said nozzle, a sealing washer carried by said nozzle, a sealing washer carrying part in said nozzle, said nozzle rotative relative thereto, stop means between said sealing washer carrying part and said nozzle for limiting the extent of rotative movement of said nozzle 80 relative to said sealing washer carrying part, and means between said sealing washer carrying part and said lubricant-receiving part for holding said sealing washer carrying part stationary, rotatively considered, relative to said lubricant-receiving part during at least a portion of the rotation of said nozzle relative to said lubricant-receiving part.

11. A lubricating system comprising, in combination, a lubricant-receiving part having an opening in the end thereof, projections adjacent said end, in combination with a lubricant-delivering nozzle having an opening in the end thereof shaped to admit 90 said end of said part and said projections, said nozzle shaped to permit turning thereof relative to said projections when the latter are entered in said nozzle, so that said projections overlie locking portions of said nozzle, a sealing washer carried by said nozzle, a sealing washer carrying part in said nozzle, said nozzle rotative relative thereto, stop means between said sealing washer carrying part and said nozzle for limiting the 100 extent of rotative movement of said nozzle relative to said sealing washer carrying part, means between said sealing washer carrying part and said lubricant-receiving part for holding said sealing washer carrying part 110 stationary, rotatively considered, relative to said lubricant-receiving part during at least a portion of the rotation of said nozzle relative to said lubricant-receiving part, and valve means connected to said nozzle and 115 connections for opening said valve means by rotative movement in the direction which connects said nozzle and said lubricant-receiving part and conversely for closing said valve means by rotative movement in the 120 direction which disconnects said nozzle and said lubricant-receiving part.

12. In a lubricating system, the combination of a lubricant-receiving member providing lateral projections, a lubricant-delivering member comprising an end portion having an opening therein to receive the end of the lubricant-receiving member and presenting interior flanges to be overlain by 125 said projections when said end portion is 130

turned relative to said lubricant-receiving member, and a part within said end portion held against turning movement by said lateral projections during turning movement of said end portion.

13. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, and a part within said end portion held against turning movement during turning movement of said end portion, said part carrying a sealing element for sealing the joint at the end of said lubricant-receiving member.

14. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, a part within said end portion carrying a sealing element for sealing the joint at the end of said lubricant-receiving member and means fitting over said lateral projections to oppose turning movement of said part when said end portion is turned.

15. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, and a part within said end portion held against turning movement during turning movement of said end portion, a sealing element carried by said part for sealing the joint at the end of said lubricant-receiving member, said sealing element lubricant-pressed toward said lubricant-receiving member.

16. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, a sealing part within said end portion held against turning movement during turning movement of said end portion, valve means and valve-operating means actuated

by relative turning movement between said sealing part and a cooperating rotatable part.

17. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, sealing means and valve means within said end portion, said sealing means engageable with the lateral projections and providing a seal against the end of the lubricant-receiving member.

18. In a lubricating system, the combination of a lubricant-receiving member providing lateral projections, a lubricant-delivering member comprising an end portion having an opening therein to receive the end of the lubricant-receiving member and presenting interior flanges to be overlain by said projections when said end portion is turned relative to said lubricant-receiving member, sealing means and valve means within said end portion, said sealing means held against rotation by said projections, and said valve means partly held against rotation with said end portion and partly mounted for turning movement therewith.

19. In a lubricating system, the combination of a nipple including a body portion having a lubricant-receiving opening at one end, an enlarged portion on said body portion and presenting a plurality of symmetrically arranged, extended, lateral and underlying surfaces and a lubricant-delivering member having an opening in the end thereof generally corresponding to the cross-sectional shape of said enlarged portion and interiorly chambered to present interior flanges to be overlain by said underlying surfaces when said end portion is turned relative to said nipple and a sealing part for engagement with the end of said nipple and secured against substantial axial movement relative to said lubricant-delivering member.

20. In a lubricating system, the combination of a nipple including a body portion having a lubricant-receiving opening at one end, an enlarged portion on said body portion and presenting a plurality of symmetrically arranged, extended, lateral and underlying surfaces, a lubricant-delivering member having an opening in the end thereof generally corresponding to the cross-sectional shape of said enlarged portion and interiorly chambered to present interior flanges to be overlain by said underlying surfaces when said end portion is turned relative to said nipple, and means for making a seal between the nipple and the de-

livering member, said means located within said delivering member and presenting surfaces bearing against said lateral surfaces of said enlarged portion of said nipple to prevent turning thereof relative to the nipple.

21. In a lubricating system, the combination of a nipple including a body portion having a lubricant-receiving opening at one end, an enlarged portion on said body portion and presenting a plurality of symmetrically arranged, extended, lateral and underlying surfaces, a lubricant-delivering member having an opening in the end thereof generally corresponding to the cross-sectional shape of said enlarged portion and interiorly chambered to present interior flanges to be overlain by said underlying surfaces when said end portion is turned relative to said nipple, and means within said end of said delivering member, mounted for turning movement relative thereto and presenting surfaces bearing against said lateral surfaces of said enlarged portion of said nipple, said means limiting turning movement between said nipple and said delivering member.

22. In a lubricating system, the combination of a nipple including a body portion having a lubricant-receiving opening at one end, an enlarged portion on said body portion and presenting a plurality of symmetrically arranged, extended lateral and underlying surfaces, a lubricant-delivering member having an opening in the end thereof generally corresponding to the cross-sectional shape of said enlarged portion and interiorly chambered to present interior flanges to be overlain by said underlying surfaces when said end portion is turned relative to said nipple, a valve controlling discharge of lubricant from said lubricant-delivering member, and means within said end of said delivering member, mounted for turning movement relative thereto and presenting surfaces bearing against said lateral surfaces of said enlarged portion of said nipple, said means actuating by turning movement relative to said end the opening and closing of said valve.

23. In a lubricating system, the combination of a nipple including a body portion having a lubricant-receiving opening at one end, an enlarged portion on said body portion and presenting a plurality of symmetrically arranged, extended, lateral and underlying surfaces, a lubricant-delivering member having an opening in the end thereof generally corresponding to the cross-sectional shape of said enlarged portion and interiorly chambered to present interior flanges to be overlain by said underlying surfaces when said end portion is turned relative to said nipple, a valve controlling

discharge of lubricant from said lubricant-delivering member, and means within said end of said delivering member, mounted for turning movement relative thereto and presenting surfaces bearing against said lateral surfaces of said enlarged portion of said nipple, said means limiting turning movement between said nipple and said delivering member and said means actuating by turning movement relative to said end, the opening and closing of said valve.

24. Lubricating apparatus comprising, in combination, a lubricant-receiving nipple and a lubricant-expelling device providing a coupling having an axial opening to receive said nipple by direct axial entrance and interiorly chambered to permit subsequent turning of said device relative to said nipple to effect the coupling operation, and valve means carried by said coupling and presenting a plurality of extensions for engagement with said nipple to provide for opening of said valve.

25. A lubricating system comprising a lubricant-delivering nozzle and a lubricant-receiving nipple, interlocking means for coupling said nozzle and nipple by axial telescoping and rotary movement, sealing means in said nozzle for pressing against said nipple to form a lubricant-tight seal, and means for preventing rotation of said sealing means with respect to said nipple when pressed against said nipple.

26. A lubricating system comprising a lubricant-delivering nozzle and a lubricant-receiving nipple, interlocking means for coupling said nozzle and nipple by axial telescoping and rotary movement, means in said nozzle having limited axial and rotary movement and locked against rotation with respect to said nipple by said axial telescoping movement, a sealing member carried by said locked means for sealing contact with said nipple, and valve means actuated by rotation of said nozzle with respect to said locked means for opening and closing a passage through said nozzle.

27. A lubricating system comprising a lubricant compressor having a delivering nozzle connected thereto and a lubricant-receiving nipple, coupling means requiring axial telescoping and subsequent rotation to couple said nozzle and nipple, sealing means operatively juxtaposed by said axial movement, and rotary valve means opened by said subsequent rotation.

28. A lubricating system comprising a lubricant compressor having a delivering nozzle connected thereto and a lubricant-receiving nipple, coupling means requiring axial telescoping and subsequent rotation to couple said nozzle and nipple, sealing means operatively juxtaposed by said axial movement, valve means opened by said subse-

quent rotation, and means for preventing rotation of said sealing means on said nipple after sealing.

29. Lubricating apparatus comprising a lubricant gun having a discharge nozzle presenting a lubricant-pressed sealing part for engagement against the end of a lubricant receiving nipple, a rotary valve co-operating therewith, and a coupling for engagement 10 with a lubricant receiving nipple presenting coupling projections.

30. Lubricating apparatus comprising a lubricant expelling device presenting a nozzle having a generally polygonal opening in

the end thereof for engagement over a lubricant receiving element presenting a portion generally polygonal in cross section and including projecting portions, flanges adjacent said opening adapted to underlie the projections when said nozzle is turned relative thereto, said nozzle presenting a rotary valve having ports adapted to be brought into and out of alignment with each other.

In testimony whereof, we have signed our names to this specification.
